UNITED STATES PATENT OFFICE.

EDWARD W. ARNOLD, OF NORTH ABINGTON, MASSACHUSETTS.

WELTING.

Application filed September 20, 1926. Serial No. 136,487.

The invention to be hereinafter described relates to welting for use in the manufacture of shoes, and a method of making the welting.

The usual welting consists of a leather strip having flesh and grain faces, and edges perpendicular to said faces, a groove or channel for the inseam stitching being formed in the flesh side of the body of the welting adjacent the inner edge thereof. The grain face 5 is beveled at the inner edge to increase the flexibility of the welting and in order that the bevel and inner edge may fit snugly in the angle between the feather and lip at the edge of the insole.

15 Welting should be made of high grade leather having the toughness and strength necessary to hold the inseam and outseam stitching. This leather is expensive and therefore it is important that strict economy 20 should be practiced in the amount of material used in making the welting. Even a slight saving in the width of the leather strip used in making the welting is very important to the manufacturer who makes and sells many 25 thousand yards of welting per day.

The present invention provides simple, strong, efficient welting which can be easily and cheaply manufactured with desirable economy of material.

30 The character of the invention may be best understood by reference to the following description of the method of making one good form of the welting shown in the accompanying drawing, wherein:

35 Fig. 1 on an enlarged scale is a transverse section through the strip of leather from which the welting is formed;

40 Fig. 2 is a transverse section through the strip showing the incision made through the flesh face of the body of the strip and inclined toward an edge of the strip;

45 Fig. 3 is a transverse section through the strip showing the body portion between the incision and the inner edge of the strip pressed outward to final form;

Fig. 4 is an actual size transverse section through welting made by the method;

50 Fig. 5 is a transverse section through a portion of a shoe having a welt embodying the invention; and

Fig. 6 is a transverse section through the shoe and showing the outer sole applied.

In the method of making the welting a strip 1 (Fig. 1) of leather is formed by slitting the strip from stock so that in the present instance it is of substantially rectangular

cross section with edges 3 and 5 substantially perpendicular to the flesh face 7 and the grain face 9 of the body of the strip.

An incision 11 (Fig. 2) is made in the body 60 of the strip through the flesh face near its inner edge, and in the present instance it is inclined toward the inner edge and is of a depth sufficient to extend substantially half way through the thickness of the strip. 65 While the incision shown is formed by a straight cut, it will be understood that it might be otherwise formed.

Next the body portion 13 between the incision 11 and the inner edge of the strip is 70 bent or pressed or set outward to open the incision and form the groove or channel 15 (Fig. 3) which is adapted to receive the inseam stitching, as more fully hereinafter described. In pressing the body portion outward the inner edge 3 forms a bevel 17 at an obtuse angle with respect to the grain face of the strip, and in the present instance the edge 19 of the body portion is brought outward to a position where it is opposite to the line of juncture of the inner edge with the grain face of the strip, while the edge 21 of the body portion is brought outward a substantial distance beyond the inner edge of the grain face of the strip. The body portion 75 13 may be tapered somewhat in transverse section as appears in Fig. 2, but it may be pressed to give it the form of the body portion 23 (Figs. 3 and 4). The pressing out and shaping of the body portion may be performed in one operation. 80

As stated, in the old welting the inner edge is beveled to enable it to be seated snugly into the angle formed by the insole feather and lip, and lie in proper position to receive 95 the inseam stitching. By the present method the bevel of the inner edge is inherent to the pressing out of the body material at the inner side of the incision as described, so that it is not necessary to remove material 100 from the welting in producing the beveled edge, and at the same time welting of the same overall width as the old welting can be made from a strip which is narrower than the strip used in making the old welting. As 105 a consequence the present method enables an important saving in material. For example, it may be supposed that the ordinary welting is made from a leather strip having a width of $\frac{1}{6}$ of an inch and that $\frac{1}{16}$ of an inch of the grain face is removed by the bevel. In 110 the practice of the present method a narrower

strip may be employed, such, for example, as one having a width of $\frac{7}{16}$ of an inch. By making the incision in this narrower strip and pressing outward the body material between the incision and the inner edge as described, the original overall width of the strip may be increased $\frac{1}{16}$ of an inch, thereby producing an $\frac{8}{16}$ of an inch width welting. When it is considered that the output of the 10 welting manufacturer is thousands of yards per day, it will be readily appreciated that welting made by the present method effects a very substantial economy.

Having described the method and the welting produced by the practice thereof, next will be described the application of the welt to a shoe. Referring to Fig. 5, 25 designates an inner sole having a feather 27, a lip 29 and stitching receiving rib 31. A welt 30 embodying the invention has its inner bevel edge fitted snugly into the angle between the feather and lip of the inner sole, the marginal portions of the upper 35 and its lining 37 being interposed between the adjacent 20 edges of the inner sole and the welt, and said parts being secured together by the inseam stitching 39. Edge portions of the welt, inner sole, upper and lining are then trimmed off along the line X—X (Fig. 5). After 30 beating out the welt in the usual manner the filler 41 is laid on the inner sole within the boundary of the welt, and the welt and the outer sole 43 are secured together by the out-seam stitching 45, as shown in Fig. 6.

There are important advantages in making 35 welting by the method set forth herein. Welting of the same width as the previous welting can be produced from a strip of less width, or starting with a strip of the same 40 width as heretofore, wider welting can be obtained, and in either case the bevel of the inner edge is obtained without skiving and removal of stock and consequent waste. The full width of the grain face of the strip is retained and there is no unfinished surface 45 of the welt exposed in the finished shoe. The channel is located so that the inseam stitching will pass through the inner margin of the grain face of the welt, and the marginal 50 or body portion pressed outward and formed as above described presents a strong, substantial ridge effective to resist the tearing strain of the stitching. This ridge with its beveled edge increases the pliability of the welt and 55 facilitates its bending around the toe of the shoe. The welting is simple and strong in construction, and can be easily and cheaply manufactured.

It will be understood that the invention is 60 not limited to the specific embodiment of the welting and the method of making the same disclosed herein, and that various deviations can be made therefrom without departing from the spirit and scope of the appended 65 claims.

What is claimed is:—

1. A method of manufacturing welting for shoes characterized by making a longitudinal incision in the body of a leather strip near an edge thereof, and pressing outward 70 the portion of the strip between the incision and said edge to open the incision, set the inner edge out to be oblique to the grain face, and increase the width of the strip.

2. A method of manufacturing welting 75 for shoes characterized by making a longitudinal incision partly through and near an edge of the body of a leather strip which is perpendicular to the flesh and grain faces of the strip, and pressing outward a portion of 80 the body between the incision and said perpendicular edge to form a groove for receiving stitching, and to set the inner edge of the strip out to be oblique to the grain face.

3. A method of manufacturing welting for 85 shoes characterized by making a longitudinal incision part way through a strip of welting material near an edge thereof, setting outward the portion of the body between said incision and edge to open the incision, form 90 a channel and cause the inner edge of the strip to be oblique to the grain face, and pressing said portion to final form.

4. A method of manufacturing welting for 95 shoes characterized by cutting inwardly from the flesh face of a blank strip of substantially rectangular cross section longitudinally thereof and adjacent to one edge of the strip to partially sever a marginal portion, and bending said marginal portion in a manner 100 to open up the incision to form a stitch receiving groove, set out the outer edge of said portion to be oblique to the grain face, and widen the strip.

5. As an article of manufacture, welting 105 for use in making welt shoes, comprising a strip of welting material having an incision adjacent an edge of the strip and extending longitudinally thereof, a marginal portion between said incision and edge being bent outwardly, and the outer edge of said portion and the grain face forming an obtuse angle.

6. As an article of manufacture, welting 115 for use in making welt shoes, comprising a strip of leather having flesh and grain faces and inner and outer edges, an incision through the flesh face extending into the strip transversely to said faces, a marginal portion between the incision and the inner 120 edge being pressed outward from the line of juncture of the grain face with the inner edge of the strip, and the outer edge of said portion being oblique to the grain face of the strip.

7. As an article of manufacture, welting 125 for use in making welt shoes comprising a strip of leather having flesh and grain faces and inner and outer edges, an incision through the flesh face and extending part 130

way through the strip, a marginal portion between the incision and inner edge being bent outward and toward the grain face, said portion being pressed and providing a substantial stitch resisting ridge and the outer edge of said portion and the grain face forming an obtuse angle.

8. Welting comprising a strip of substantially rectangular cross-section having the portion along one edge thereof partly severed therefrom by an incision extending inwardly from the flesh face, said partly severed portion being bent back from the flesh face toward the grain face, and the outer edge of said portion being oblique to the grain face.

9. Welting comprising a leather strip of substantially rectangular cross section having a portion partly severed therefrom by an

incision extending longitudinally of the strip adjacent to one edge thereof and extending toward said edge, said partially severed portion being bent back from the flesh face toward the grain face of the strip presenting an inseam receiving groove and an outer edge at an obtuse angle to the grain face of the strip.

10. Welting for boots and shoes comprising a strip of grain leather having a stitch-receiving groove of substantial width and requisite depth in its flesh side near its inner edge and a bevel at the inner edge of the strip formed from an outward displacement of said inner edge and of the stock which was in said groove.

EDWARD W. ARNOLD.
